UNITED STATES PATENT OFFICE.

FRANK WAGNER, OF SIDNEY, IOWA.

DESIGN FOR A COUNTER-MAT.

SPECIFICATION forming part of Design No. 30,175, dated February 14, 1899.

Application filed November 19, 1898. Serial No. 696,944. Term of patent 7 years.

To all whom it may concern:

Be it known that I, FRANK WAGNER, a citizen of the United States, residing at Sidney, in the county of Fremont and State of Iowa, have invented or produced a new and useful Design for a Counter-Mat, of which the following is a full, clear, and exact description.

This invention is a new and useful design for counter-mats intended for use on store-counters to receive coins; and the essential feature of the design resides in the circular form of the mat and the concentric circular corrugations or ridges.

The drawings hereto annexed fully illustrate the invention, in which—

Figure 1 is a top plan view of a mat constructed in accordance with my design, and Fig. 2 is a vertical sectional view.

Referring to the drawings, A indicates the mat, which may be of any desirable material and is made circular in form, and, furthermore, said mat is so constructed that it vir-

tually consists of a series of concentric circular corrugations or ridges B. The outer edge of the mat C extends downwardly and at its lower end is given a slight roll or upward turn, as indicated at D.

From the above description, taken in connection with the accompanying drawings, it will be noted that I have produced a novel design of counter-mat, capable of holding the coin in a position convenient to be grasped, as the coin will rest in one of the depressions and lean against one of the adjacent ridges or corrugations.

Having thus fully described my invention, what I claim as new, and desire to secure by Letters Patent, is—

The design for a counter-mat, substantially as shown and described.

FRANK WAGNER.
